UNITED STATES PATENT OFFICE.

WAYNE C. VAN GILDER, OF HAMMOND, INDIANA.

DRAFTING INSTRUMENT.

1,007,992.

Specification of Letters Patent.

Patented Nov. 7, 1911.

Application filed September 30, 1910. Serial No. 584,660.

To all whom it may concern:

Be it known that I, WAYNE C. VAN GILDER, a citizen of the United States, residing at Hammond, in the county of Cook 5 and State of Indiana, have invented new and useful Improvements in Drafting Instruments, of which the following is a specification.

This invention relates to drafting instruments and designs more particularly to provide an instrument for laying out elbow patterns, T patterns and other patterns for angular joints for pipe or other conduits.

The object of this invention is to provide 10 a comparatively simple and inexpensive instrument which may* be readily adjusted for any given size of pipe, within predetermined limits, and being provided with a flexible edge which, when the parts are 15 properly adjusted, assumes a regular part 20 of the desired curve used in laying out the pattern.

To such end this invention consists in a drafting instrument having two angularly 25 disposed members, relatively movable with respect to each other, and adapted to be locked together against relative movement at various positions with respect to each other, and a flexible element secured to one 30 of said movable members and guided on the other member and arranged to be sprung into a curve of given direction by the adjustment of one of the members upon the other.

The invention further consists in the several novel features of construction and arrangement set forth in this specification and more particularly pointed out in the claims appended hereto.

The invention is clearly illustrated in the drawings furnished herewith in which—

Figure 1 is a plan of an instrument embodying my present invention, Fig. 2 is an edge view thereof looking in the direction 45 of the arrow 2, in Fig. 1, Fig. 3 is a plan, viewed from below, of a slide, with certain portions broken out to show parts which would otherwise be hidden from view, Fig. 4 is an end view of said slide, Fig. 5 is an 50 end view of one of the relatively movable members of the instrument, the view being taken in the direction indicated by the ar-

row 5 in Fig. 1, Fig. 6 is a detail, vertical section taken on the line 6—6 of Fig. 1, Fig. 7 is a detail, vertical section taken on the line 7—7 of Fig. 1, Fig. 8 is a horizontal section taken on the line 8—8 of Fig. 7, Fig. 9 is a vertical section taken on the line 9—9 of Fig. 8, Fig. 10 is an end view of one of the relatively movable members showing a 55 certain clamp, the view being taken in the direction of the arrow 10, in Fig. 1, Fig. 11 is a detail, horizontal section taken on the line 11—11 of Fig. 10, Fig. 12 is a side view of an elbow, Fig. 13 is a view of a 60 pattern drafted with the instrument.

Referring to said drawings, two relatively movable members A, B, will be seen in Fig. 1, said members being adjustably connected together by a slide C, which may 65 be clamped to either or both of said members, as desired.

The member A, is preferably in the form 70 of a bar 10, of suitable length, having linear divisions upon its edges. The member A, 75 bears a second set of graduations 11, which may be arranged upon a second bar 12, preferably narrower than the bar 10, and raised above the same, as by struts 13. This peculiar construction is not material to my 80 invention, broadly considered, but the raised bar 12, provides a convenient means for receiving and guiding the slide C; said slide C in such case being provided with ribs 15, having overhanging flanges 14, adapted to 85 project beyond the struts 13. The edges 15^a, of the ribs 15, are parallel and fit against the side edges of the raised bar 12, so that the slide may move in a perfectly 90 straight line along the same. A convenient means for clamping the slide upon the member A, comprises an eccentric clamp 16, mounted upon a pin 17, and having a finger piece 18, projecting beyond the slide 95 C, which at this point is formed into a curved or arc shaped extension 19, projecting beyond the main body thereof. One rib 15, is slit to form a tongue 20, against which the eccentric clamp 16, bears and by 100 turning the handle 18, in the direction indicated by the arrows in Figs. 1 and 3, the slide may be clamped to the bar 12, of the member A, the eccentric clamp securing

the bar 12, tightly between the tongue 20 and opposite edge 15^a.

The member B, lies at right angles to the member A, and is slidably mounted in the slide C, whereby it may be adjusted into various positions at right angles to the member A. The slide is slotted horizontally above the ribs 15, as at 21, to receive the member B, and said member B, is guided 10 between the opposite edges of downwardly projecting ribs 22, 23, of the slide C, the edges of said ribs being made perfectly true and at right angles to the edges 15^a of the ribs 15, whereby the member B, may be 15 held absolutely at right angles to the member A, at all times while the pair are connected together by the slide C. If desired the rib 23, may be slit to form a tongue 24, and an eccentric clamp 25, may be mounted 20 upon the pin 17, to clamp the member B, to the slide. The construction of the eccentric clamp 25, is similar to that of the eccentric clamp 16, but it is to be understood that this particular kind of clamping means 25 is not essential to my invention broadly considered, as any well known equivalent clamping means may be employed to clamp the members A, B, together.

Detachably secured upon the working end 30 b, of the member B, is a flexible element D, which as shown in the drawing comprises a bar or strip of flexible metal, preferably steel. Said bar is detachably secured upon the working end of the member B, by a 35 clamp, here shown as comprising a head 27, fast on the end of the member B, a flanged clamping plate 26, spaced away from the head 27, by a strut 28, and held in place by screws 29. The flanged clamping plate 26, 40 is preferably provided with overhanging flanges 30, so as to provide a seat for the strut 28, and bar D, and a set screw 31, is threaded in the head 27, and bears upon the outer face of the flanged clamping plate 26, 45 to clamp the bar D, in place. If desired the bar may be slotted as at d^a, to receive the threaded shank of the set screw 31. The construction just described furnishes a simple clamp for securing one end of the flexible element D, in place upon the working 50 end of the member B, but it is perfectly obvious that other well known forms of clamping means may be used without departing from the spirit of my invention.

55 The flexible element D, slides in a guide E, located at one end of the member A, the object being to maintain any point on the edge d¹⁰, of the flexible element at the zero point of scale 1. Said guide is preferably 60 in the form of a clamp secured upon one end of the member A, and as shown said clamp has a vertically extending lug 32, the corner 33, of which is arranged on the edge a, of the member A, and at the zero point

of the scale 1. Extending up from the member A, is a vertical support 34, in which is guided a clamping head 35, as by overhanging flanges 36, formed on the support 34. The working end 37, of said head 35, is arranged to engage with the side of the flexible element D, and to hold said element tightly against the corner 33, of the lug 32. The means for adjusting said head 35, is shown to comprise a set screw 38, threaded in an internally threaded tubular member 39, stationarily secured to the member A, as by soldering or riveting it to the support 34. The screw 38, is connected to the head 35, as by a link 40, which may be fastened to the head 35, as by a screw 41, and which extends into a socket in the screw 38, where it is provided with a reduced neck 42, in which seats a pin 43, secured in the screw. This particular construction permits the screw to be turned to adjust it along its support 39, without turning the link 40. The screw is provided with an ordinary head by which it may be turned by hand to move the clamping head 35, into or out of engagement with the flexible element D. It is to 80 be observed that while this construction forms a very simple guide and clamp, other equivalent devices may be substituted for it.

The marks, respectively designated by numerals 1—2 etc. on the scale 11, which numerals indicate pipe diameters in inches, are each located at a distance from the zero point on the scale, equal to the numeral multiplied by 3.1416 divided by 4 inches. The member B is shown as set at "10", on the scale 11, for drawing a pattern in which the diameter of each elbow section is 10 inches. The distance of the point "10" away from the zero point on the scale 11, is equal to ten inches times 3.1416 divided by 4; in other words 105 it is equal to one fourth of the circumference of a circle whose diameter is 10 inches.

The member B, is provided with a number of scales or graduations d, d¹, d², d³, d⁴, d⁵, which determine the highest point of the 110 curve; namely the point x on the pattern; said scales may be determined as follows: In the three piece elbow shown in Fig. 12, a base line b—b, is drawn which intersects the meeting line between two sections of the 115 elbow, at its middle point. The distance between the point x and the base line is equal to the proper distance between the point X on the member B, and the edge a, of the member A. This distance is graduated into smaller divisions corresponding in 120 number to the divisions on the scale 11. The scales for 4 piece patterns, 5 piece patterns etc., are determined in the same way from drawings of 4 piece elbows, 5 piece elbows etc. Inasmuch as the edge c¹ of the slide is set back from the edge a, the zero points of the scales d, d¹ etc. are set back a 125

distance from the point X equal to the distance between the edges $a-c^1$. The divisions of the scales d , d^1 , etc. indicate pipe diameters in inches, as do the divisions on the scales 11.

Along the edge 44, of the member B, is a scale 45, arranged in inches and said edge 44, registers with the edge c , of the slide C. The end of flexible element D, while held 10 by the clamp, lies at right angles to the edge 44, of the member B, and some point in its length passes the zero point on the scale 1. By reason of this fact and by reason of its flexibility, said flexible element 15 will assume the correct curve or line for drafting the curved edges of elbow, T patterns or other like patterns.

In operation the slide C, and member B, are adjusted along the member A, until the 20 edge c , and edge 44, are brought into register with the dimension point upon the scale 11, indicating the diameter of the elbow pattern or other pattern which it is desired to lay out. The eccentric clamp 16, is then moved 25 over to clamp the slide in place on the member A. The member B, is then adjusted in the slide C, bringing the same dimension point thereon, as is used on the scale 11, into register with the edge c^1 . This depends 30 upon the number of pieces required to make the given elbow. The slide C, has numerals upon its edge c^1 , indicating the scale to be used for three piece elbows, four piece elbows etc., up to eight piece elbows. If a three 35 piece elbow is to be drafted, the scale marked 3 is used; if four piece the scale 4 is used and so on. When the member B, has been brought to the proper position in the slide C, the eccentric clamp 25, is moved over to 40 clamp said member B in place in the slide. The flexible element having been flexed by the movement of the member B, automatically assumes the proper curve for drawing one fourth of the curve of the pattern. The 45 adjustment screw 38, is now clamped in place to secure the drawing edge d^{10} , in engagement with the corner 33, of the lug 32.

In using the instrument, a base line $b-b$ (see Fig. 13) is first drawn on the paper 50 and the instrument placed thereon with the edge a , of the member A coincident with the base line and the curve O struck along the outer or marking edge of the bar D, said curve intersecting with the base line at a^2 , 55 and with a vertical line $a z$, (coincident with the edge 44 of the member B,) at x . The instrument is then inverted, bringing the edge 44, along the vertical line $a z$, and the edge a , on the base line $b-b$, and the line O^1 , 60 drawn; said line intersecting with the base line at a^5 . One-half of the curved line is now complete and the other two quarters may be completed by reversing the instrument and drawing the lines O^2 , O^3 . One

half of the line drawn indicates the line O^4 , 65 on the elbow shown in Fig. 12, and the other half is on the opposite side of the elbow.

From the above it is quite evident that the usual task of laying out the curve described in Fig. 13, is overcome. The device is extremely simple, accurate and efficient for the purpose for which it is intended.

I realize that various alterations and modifications of this device are possible without departing from the spirit of my invention, and I do not therefore desire to limit myself to the exact form of construction shown and described.

I claim as new and desire to secure by Letters, Patent:

1. In a drafting instrument the combination of two connected, angularly disposed, relatively adjustable members, each having a straight edge disposed at right angles to the other, a flexible element secured to one member at right angles thereto, and a guide secured upon the other member, and having a guiding edge located at a fixed point on the straight edge of said other member and arranged to guide the flexible element across 85 said fixed point, substantially as and for the purpose set forth.

2. In a drafting instrument, the combination of two relatively adjustable members, each having a straight edge disposed at 95 right angles to the other, a slide having two guideways disposed at right angles to each other, for receiving and guiding said adjustable members, clamping means associated with said slide for clamping said adjustable 100 members in place, a spring steel bar detachably secured to one of said members to extend at right angles thereto, and a guide having a guiding edge located at a fixed point on the straight edge of the other member and arranged to guide said spring steel 105 bar across said fixed point on the straight edge.

3. In a drafting instrument, the combination of two relatively movable members, 110 each having a straight edge arranged at right angles to the other, and one member having graduations thereon representing diameters, and the other member having a plurality of sets of graduations thereon, in fixed 115 proportion to the first mentioned graduations, substantially as described, a slide for connecting said members together, a flexible, spring steel bar secured to the second named member at the zero end of the graduations 120 thereon and extending at right angles to said member, and a guide secured to the first named member at the zero point of the graduations thereon, and arranged to guide the steel bar across the straight edge thereof 125 at the zero point thereon.

4. In a drafting instrument, the combination of two connected, angularly disposed,

relatively adjustable members, each having a straight edge disposed at right angles to the other, a flexible element secured to one member at right angles thereto, and a guide 5 secured upon the other member, and having a guiding edge located at a fixed point on the straight edge of said other member and arranged to guide the flexible element across said fixed point, said guide having a clamping 10 plate arranged to bear against the flexible

element to hold the same in place and a set screw for pressing the plate against said flexible element.

In witness whereof I have hereunto signed my name at Hammond, Lake county, Indiana, this 28th day of September 1910. 15

WAYNE C. VAN GILDER.
